UNITED STATES PATENT OFFICE.

WILLIAM DRAPER ANDREWS, OF BROOKHAVEN, NEW YORK.

PUMP.

SPECIFICATION forming part of Letters Patent No. 390,332, dated October 2, 1888.

Application filed March 2, 1886. Serial No. 193,762. (No model.)

To all whom it may concern:

Be it known that I, WILLIAM DRAPER ANDREWS, of the town of Brookhaven, county of Suffolk, in the State of New York, have invented a new and useful Improvement in Pumps, of which the following is a specification.

This invention relates to what I term an "impetus centrifugal pump," in which the water is moved by the rotary motion imparted to it through a rotary wheel provided with blades which project into, but do not fit tightly in, a circumferential annular channel in the pump-casing, with which the suction and discharge pipes communicate. An example of a pump upon this principle is shown in my United States Letters Patent No. 110,330, granted December 20, 1870.

Important objects of my invention are to provide a novel combination of the casing and wheel of such a pump as will enable comparatively large bodies of solid material to pass with the water through the pump without choking the pump or cramping the rotary wheel; also, to provide a novel construction of wheel which is very light and so formed and combined with the casing as to prevent dirt or grit from getting into the bearings of the wheel-shaft and cutting and wearing said bearings and shaft; also, to so construct the casing that the two halves or sections of which it is composed may be cast from a single pattern; also, to so construct and combine the pump-casing with its feet or standards that it may be set in any desired position with its suction and discharge nozzles presented in any desired direction, and to provide for the suction and discharge of water, either vertically or horizontally when the pump is so supported that its suction and discharge nozzles are equally above and below a horizontal plane intersecting the axis of the pump, or in other desired directions when the pump is otherwise arranged; also, to provide a simple and easily-adjustable packing, whereby dirt or grit is prevented from reaching the shaft and bearings, and whereby leakage of air or water through the shaft-bearings or between the bearings and case-hub is prevented; also, to provide for readily removing one half or section of the casing when desired without dis-

turbing the other half of the casing, the rotary wheel and its driving mechanism, or the suction or discharge pipes.

The invention consists in novel combinations of parts and features of construction hereinafter described, and pointed out in the claims, whereby the aforesaid and other advantages are attained.

In the accompanying drawings, Figure 1 is a vertical section of a pump embodying my invention in a plane transverse to the pump-shaft. Fig. 2 is a vertical section in a plane parallel with the shaft. Fig. 3 is a side elevation of the pump, and Fig. 4 is a similar side elevation showing the casing supported in a different position.

Similar letters of reference designate corresponding parts in all the figures.

A designates the wheel of the pump, which is secured fast upon a shaft, B, to which rotary motion may be imparted either by a belt running on a driving pulley, C, or by direct connection with an engine-shaft through the coupling C'. The wheel rotates in a casing composed of two halves or sections, D D', united at their periphery by a flanged joint, d, secured by bolts d'. The casing has inlet or suction and discharge nozzles D² D³, with which suction and discharge pipes may be connected, and the two halves or sections are formed with projecting lugs or bearers d', which rest upon and are to be bolted to feet or legs d'', whereby the pump is supported. The casing is constructed with an annular channel or water-way, D⁴, with which the suction and discharge nozzles D² D³ communicate, and between the two nozzles is an abutment, D⁴. This abutment may consist of a hollow casting formed integral with the sections D D'. By the rotation of the wheel A in the direction of the arrows in Fig. 1 the water entering from the suction-nozzle D² is caused to take the same direction, as also indicated by arrows in said figure, and is discharged at the nozzle D³.

The two halves or sections D D' of the casing have hubs or bosses e e' at the center, and radiating therefrom are strengthening ribs d''. The hub or boss e is bored out to receive a bushing or sleeve, f, which forms one of the bearings for the shaft B, and the hub or boss e' is bored out to receive a follower or bonnet,

f', which is connected with the casing by bolts *g*, and which has a long neck, *f*², forming a long bearing for the shaft *B*, and on the exterior of which is journaled the pulley *C*. The 5 pulley is loose on the follower or bonnet *f'f*², and is connected with the end of the shaft *B* by a coupling, *C'*, of any suitable construction—such, for example, as that shown in my Patent No. 156,523, granted November 3, 1874.

10 The belt may be led from any direction to the pulley *C* without interfering with the bearers *d*² or the feet or legs *d*².

Between the sleeve or bushing *f* and the follower or bonnet *f'* and the opposite ends of the hub or center *a* of the wheel *A* are arranged packings consisting of metal rings *g'* and india rubber or other elastic packing-washers, *g*². The metal packing-rings *g'* and the elastic packing-washers *g*² fit snugly within 15 the inner ends of the hubs or bosses *e*, but are not in contact with the wheel-shaft, which passes freely through them, the inner ends of the packing-rings being in contact with the outer ends of the wheel hub or center, and the 20 elastic washers being between the metal rings and the ends of the bushing and follower. The outer end of the hub *e* of the casing is closed air-tight by a cap or bonnet, *e*², through which are inserted adjusting-screws *e*³, bearing on the 25 sleeve or bushing *f*, and a screw, *e*⁴, bearing on the end of the shaft *B*. By means of the screw *e*⁴ and the bolts *g* the wheel may be properly adjusted in the casing, and by means of the screws *e*³ all wear in the packings *g'g*² may 30 be taken up. By means of these packings dirt and grit are prevented from getting into the shaft-bearings, and leakage through and past the shaft bearings is prevented.

I will now describe the construction of the 40 wheel *A* and its combination with the casing, which are important features of my invention.

In what I now consider a preferable form the wheel consists of flat plates or disks *a'*, which are bolted or riveted to the hub or center *a*, and may be of steel or other sheet or plate metal, and wings or blades *a*², which project into and move in the annular channel or water-way *D*². The hub or center *a* is secured to the shaft *B* by a set-screw, *a*³, or otherwise, and has flanges *a*⁴, to which the side plates, *a'*, are secured. The blades *a*² are also 45 of plate or sheet metal, and have portions which are bent at right angles to them to form ears or flanges *a*⁵, whereby the blades are secured with bolts or rivets to the side plates, *a'*.

50 When the pump is in operation, all dirt and grit in the water will be thrown to the circumference of the casing by centrifugal force, and will pass through the annular passage *D*² of the pump freely; but when the wheel *A* is stopped all dirt or grit in the water will fall to the bottom of the pump. The construction of the wheel with the side plates, *a'*, and the free opening between them, intercepted 55 only by the small diameter of the hub or center *a*, allows all dirt or grit to fall to the bottom of the pump without coming in contact

with the shaft *B* or its bearings, and the side plates, *a'*, prevent dirt from getting into the packings *g'g*² and the shaft bearings. This important result is still further secured by constructing the sections *D D'* of the casing at the inner circumference of the annular channel *D*² with inwardly-projecting lips or flanges *d*², which overlap the edges of the side plates, 70 *a'*, and under cover of which said plates turn, as shown in Fig. 2. The side plates, *a'*, may work as closely as possible to the sides of the casing, so that little water may at any time be between the side plates and casing. 80

As shown in Fig. 2, the blades *a*² are of segmental form and work in near proximity to the inner circumference of the annular channel *D*²; but they do not project nearly to the outer wall of the channel, and beyond their 85 outer edges there is formed in the channel a water-way of sufficient capacity to permit the passage of large solid bodies without choking the pump or cramping the wheel. As here represented, the blades *a*² do not project to the center of the channel *D*², and the free water-way is therefore more than half the sectional area of the channel *D*².

As best shown in Fig. 2, the two sections *D D'* are supported by separate and independent feet or legs *d*², and consequently the section *D* may be removed to afford access to the wheel *A* without disturbing the section *D'*, or the wheel and driving-shaft and pulley, or the suction and discharge pipes. To steady the 100 section *D'* when the section *D* is removed, I have represented a supplemental foot or leg, *d*⁵, attached to the flanged joint *d*, as seen in Fig. 2.

The sections *D D'* of the casing are constructed with a circular series of lugs or bearers, *d*², as shown in Figs. 3 and 4, and any two of these bearers may rest upon the feet or legs *d*². This provides for adjusting the pump-casing so that the suction and discharge nozzles *D*² *D*³ will have any desired position. The pump-casing may be arranged so that said nozzles will be equally above and below a horizontal plane intersecting the axis of the pump, as indicated by the dotted line *s s*, Figs. 1 and 105 3, or so that the two nozzles will have the position shown in Fig. 4 or any other desired position.

The nozzles *D*² *D*³ are preferably curved and have their flanged faces located at equal angles 110 relatively to a line, *s s*, drawn midway between them and intersecting the axis of the pump, and this construction enables both casing-sections *D D'* to be cast from a single pattern, and avoids the necessity of making right and 115 left patterns for the two sections. I also preferably provide the flanged nozzles *D*² *D*³ with elbows or bends *E*, which represent one-eighth of a circle, and the faces of which form angles of forty-five degrees (45°) with each other, and 120 are directly opposite each other. These bends may then be placed, as shown in full lines, so as to take the suction from and discharge into 125 vertical pipes, or, as shown by dotted lines, so

as to take suction from and discharge into horizontal pipes. When the pump is shifted to the position shown in Fig. 4, or to any other direction, the elbows or bends E may be set as desired to give the pipes the desired direction, either in line with the plane of the wheel's motion or at a right or other angle thereto.

The pump may be run either right or left handed to discharge either in the same direction by reversing the top for the bottom, or to discharge in an opposite direction by reversing the wheel-shaft end for end.

It will be observed that the side plates or disks, a' , of the wheel form substantially continuous and unbroken surfaces from the shaft outward to their circumference. This is important, as the sand and grit are thereby allowed a free space between the side plates through which to fall, and by the continuous surfaces of the side plates sand and grit are prevented from reaching the shaft-bearings and packings.

I use the term "substantially continuous and uniform surfaces," as applied to the side plates, to distinguish my wheel from the wheel of a blower or pump in which the blades are supported by arms radiating from a central shaft, or between plates of annular form having large openings around the shaft and supported on the shaft by spiders or arms.

What I claim as my invention, and desire to secure by Letters Patent, is—

1. The combination, with a pump-casing having an annular channel, D^* , provided with suction and discharge nozzles D^2 D^3 , and of substantially uniform caliber throughout its circumference, save for an abutment between the said nozzles, the portion of the casing between the channel and the center being contracted and of less width than the channel, of a rotary pump-wheel turning in the contracted central portion of the casing, and having blades which project beyond its periphery and are flared outward from its sides, and which project into and work snugly in the portion of the channel nearest the center of the casing and afford a free water-way beyond the outer edges of the blades, substantially as herein described.

2. The combination, with a pump-casing having an annular channel, D^* , of approximately circular transverse section, provided with suction and discharge nozzles D^2 D^3 , and of substantially uniform caliber throughout its circumference, save for an abutment between the said nozzles, the portion of the casing between the channel and the center being contracted and of less width than the channel, of a rotary pump-wheel turning in the contracted central portion of the casing and having blades which project beyond its periphery and are flared outward from its sides, and which project into and work snugly in the portion of the channel nearest the center of the casing, but which terminate inward of the center of the channel, and therefore afford a free water-

way beyond the outer edges of the blades, substantially as herein described.

3. The combination, with a pump-casing having near its periphery an annular channel provided with suction and discharge nozzles, both of which communicate with said channel, of a shaft and a rotary pump-wheel consisting of side plates which form substantially continuous and unbroken surfaces from the shaft to their outer circumference, and between which a space is afforded for falling dirt and grit, and blades attached to the side plates near their periphery and projecting into and working in said channel, substantially as herein described.

4. The combination, with a pump-casing having near its periphery an annular channel provided with suction and discharge nozzles, both of which communicate directly with said channel, and having inwardly-projecting lips or flanges d^4 , of a shaft and a pump-wheel thereon consisting of side plates which form substantially continuous and unbroken surfaces from the shaft to their circumference, and which work under cover of said lips or flanges and afford between them a space for falling dirt and grit, and blades attached to and projecting beyond the side plates into the channel and working therein, substantially as herein described.

5. The combination, with a pump-casing having near its periphery an annular channel provided with suction and discharge nozzles, both of which communicate directly with the channel, of a shaft and a rotary pump-wheel consisting of a hub or center, side plates secured to said hub and forming substantially continuous and unbroken surfaces from the shaft to their circumference and affording between them a space for falling dirt and grit, and blades secured to the side plates and projecting beyond their outer edges into said channel, substantially as herein described.

6. The combination, with a pump-casing having near its periphery an annular channel provided with suction and discharge nozzles, both of which communicate directly with the channel, of a shaft and a rotary pump-wheel secured thereon and consisting of side plates, a' , forming substantially continuous and unbroken surfaces from the shaft to their circumference and affording between them a space for falling dirt and grit, and blades a^2 , projecting beyond the side plates into the channel, and having ears a^3 projecting at right angles, and by which they are secured between the side plates, substantially as herein described.

7. The combination, with a rotary pump-wheel, of a casing having an annular channel provided with suction and discharge nozzles D^2 D^3 and made in two halves or sections, each of which is a fac-simile of the other, and which are united by a joint which is continuous through the nozzles, the two nozzles being curved uniformly, but in opposite directions from a line drawn midway between them and intersecting the axis of the pump, and the faces

of the nozzles having similar but reverse angles relatively to said line, whereby provision is afforded for casting the two halves or sections from one pattern, substantially as herein described.

8. The combination of a rotary pump-wheel and a casing having an annular channel provided with suction and discharge nozzles curved uniformly in opposite directions from a line drawn midway between them and intersecting the axis of the pump, and having their faces at the same but reverse angles relatively to said line and bends, each forming one-eighth ($\frac{1}{8}$) of a circle and secured to the nozzles, whereby the pump is adapted for use with either horizontal or vertical suction and discharge pipes by simply reversing the position of the bends, substantially as herein described.

9. The combination, with a pump-casing having hubs or hollow projections e , the shaft, and the pump-wheel secured thereon, of the sleeve or bushing f and the follower f' , fitting the hubs or hollow projections of the casing and forming bearings for the shaft, the packings consisting of metal rings g , bearing directly against the opposite sides of the wheel-hub and the elastic packing-washers g' behind the said rings, bolts g , securing the followers f' to the casing, and screws e' , bearing on the sleeve or bushing f and serving to tighten both packings, substantially as herein described.

10. The combination, with the pump-casing and the shaft and rotary pump-wheel, of pack-

ings immediately surrounding the shaft on 35 opposite sides of the wheel-hub, the sleeve or bushing f , forming one of the shaft-bearings and fitting within the hub e of the casing, the cap e^2 outside the sleeve or bushing f , and the screws e^2 , inserted through the cap e^2 , and serving, respectively, to adjust the sleeve or bushing f to tighten the packings and to adjust the shaft, substantially as herein described.

11. The combination, with a rotary pump-wheel, of a casing composed of similar halves or sections, each having a circular series of ears or bearers, d^2 , projecting laterally from its outer side near the circumference, and feet or legs d^3 , made separate from each other and from the casing, and on the upper surface of which the two halves or sections of the casing are supported independently of each other through the ears or bearers d^2 , substantially as and for the purpose herein described. 55

12. The combination, with a rotary pump-wheel, of a casing composed of similar halves or sections D D' , having separate and independent legs or feet, whereby they are individually supported, and an intermediate foot 60 or leg, d^3 , supporting the inner section, D' , at its joint, substantially as and for the purpose herein described.
